LIFTING BODY GLIDER OR THE LIKE

Joseph J. Szakacs, 1714 Washington Place,
San Diego, Calif. 92103

Filed Mar. 21, 1975, Ser. No. 560,613

Term of patent 14 years

Int. Cl. D12—07

U.S. Cl. D12—72

FIG. 1

FIG. 2

FIG. 3

FIG. 4

FIG. 5

FIG. 1 is a perspective view of a lifting body glider or the like showing my new design.

FIG. 2 is a top plan view.

FIG. 3 is a side elevation view of the left side.

FIG. 4 is a front elevation view taken in the direction of line 4—4 of FIG. 3.

FIG. 5 is an aft view taken in the direction of line 5—5 of FIG. 3.

I claim:

The ornamental design for a lifting body glider or the like, as shown.
